SINK STOPPER

Joseph B. Hernandez, New York, N. Y.

Application May 12, 1933, Serial No. 670,737

4 Claims. (Cl. 4—293)

This invention relates to sink stoppers, and more particularly to stoppers for relatively large drain openings such as are usually provided with a metal grille or perforate metal disk secured therein. Owing to the closure of the drain opening by such metal disk or grille, the conventional solid rubber stopper, or metal and rubber stopper, with tapered side wall cannot be used, and flexible disks have been devised which in use are positioned over the metal grille or perforate disk whereupon they are held, when liquid is introduced to the sink, by pressure difference above and below the rubber disk.

It is an object of the present invention to provide a flexible waterproof sink stopper of the above mentioned disk type, which shall be reliable in use with many different types and sizes of drains and which when positioned over a drain opening will resist lateral displacement.

Another object of the invention is to provide a reversible stopper by reason of which the useful life of the stopper is prolonged. Under ordinary service conditions there is a tendency for the edges of prior stoppers of this general type to curl upward at the margin until the sealing face is so far distorted as to prevent the sealing action. With the reversible structure of the present invention, the user will naturally apply it indiscriminately, or, if a tendency to curl is noted, the user will deliberately apply it reversely in making subsequent use of it.

Still another object of the invention is to provide a stopper having particular adaptability for use with widely varying drain opening diameters.

To this end the present stopper is produced with a plurality of circumferential zones formed by spaced concentric recesses in one or both sides of the disk, which weaken the disk therealong and allow for a diaphragm action including as many of the zones as may be directly over the drain opening area.

A further object is to provide a stopper of the general type referred to in which the suction may be conveniently broken for removal of the stopper from the sink.

In the accompanying drawing:

Fig. 1 is a view in plan of the improved stopper;

Fig. 2 is a view in cross section taken on the line 2—2 of Fig. 1; and

Fig. 3 is view in cross section of the stopper applied to a sink drain.

The preferred embodiment of the invention which is shown in the drawing comprises a thin piece 10 of waterproof flexible material, such,

for example, as molded vulcanized rubber compound. The piece is substantially flat, except for central projections 12 and 13 from the opposite faces 14 and 15 thereof, respectively, a series of spaced concentric grooves 16 and 17 in opposite faces, and sunken lettering or other indicia 18 in zones 20 between the grooves or between the margin 21 of the piece and its nearest groove. The projections 12 and 13 are preferably homogeneously integral with the piece 10 and of small size to enter the perforations in the metal plate across the top of the drain.

The diameter of the stopper is preferably greater than the diameter of the largest drain area usually encountered in ordinary kitchen or laboratory equipment so that when the stopper is positioned over a drain opening the margin 21 will overlie the sink bottom to a greater or less extent around the drain opening 22 or around the metal grille or perforate plate 23. This position of the stopper may be conveniently obtained by holding one of the central projections 12 or 13 between the thumb and finger and manipulating the piece until the opposite projection enters the drain or one of the perforations in the plate 23. As soon as the margin of the piece 10 contacts with the bottom of the sink and the piece is held by the interfitting projection against lateral displacement, such water or other liquid as may be let into the sink is to some extent baffled and a head of liquid builds up in the sink, which presses the central area down against the drain plate and effectively prevents the outflow of liquid. The sealing action is facilitated by such small amount of the liquid as may primarily pass between the positioned stopper and the sink and into the drain tending to carry with it the air in the drain above the conventional trap. There is thus an initial tendency to lower the air pressure below the stopper while building up a head of liquid above it.

It will be noted that the inner region of the stopper flexes as a diaphragm to conform to the usual irregularity of the sink at its outlet, the flexure taking place in largest measure between 100 juxtaposed grooves 16 and 17 at one zone or another according to the size and shape of the drain accommodated. In the drawing, Fig. 3, the drain is of a size in which the moved or flexed part includes the central zone and two surrounding zones. If the drain were of very small diameter, the central zone alone might be so displaced downward. When the diaphragm action takes place, any curl or irregularity of the outer margin of the piece which may naturally follow 110

from the movement of the inner region is insufficient to break the seal which is only broken by outside pressure applied to the margin to lift it and allow the water to enter the drain. To 5 effect this action conveniently at any point, without having to seek in opaque or extremely in-temperate liquid for any particular point of the device, the edge 24 of the stopper is extended beyond the circumference of the opposite faces 10 and preferably lies in a plane midway between the planes of the faces so that the tip or nail of the finger may be used at any point around the periphery of the stopper to lift the margin.

The reference herein to projections 12 and 13 15 as "central" is not intended to mean that they are necessarily in the exact geometrical center of the piece 10 but rather that they are in a region including and proximately surrounding the exact center.

20 What is claimed is:

1. A reversible sink stopper, comprising a thin disk of flexible waterproof material having a projection centrally from each face and spaced indentations in each face which increase the 25 flexibility of the disk, said projections being relatively narrow to permit them to enter freely into one of a plurality of small outlet holes in the drain plate and said disc as a whole being

sufficiently flexible to substantially conform under normally developed pressure differences to any irregularities in the sink at the drain portion.

2. A reversible and all flexible sink stopper, comprising a thin disk of flexible waterproof material having a peripheral edge lying in a plane midway between the planes of the opposite faces of the disk, and central projections of relatively insignificant width in comparison to the diameter of the drains that the stopper is designed to accommodate.

3. An all flexible sink stopper, comprising a thin rubber piece which is substantially flat except that it has a central projection for entering without filling the sink outlet, a peripheral edge above the plane of the bottom surface of the piece, and indicia sunk from a surface of the piece to increase the degree of its flexibility.

4. A sink stopper, comprising a thin body of vulcanized rubber composition in disk form having a narrow projection centrally from each face and a peripheral edge lying in a plane substantially midway between the faces, the projections being of a size and shape to freely enter one of a plurality of perforations in a drain plate and being substantially less in cross-area than the cross-area of the drain.
